UNITED STATES PATENT OFFICE.

THOMAS M. GYNAN, OF LEBANON, OHIO.

INNERSOLE.

Application filed February 26, 1924. Serial No. 695,317.

To all whom it may concern:

Be it known that I, THOMAS M. GYNAN, a citizen of the United States, residing at Lebanon, in the county of Warren and 5 State of Ohio, have invented new and useful Improvements in an Innersole, of which the following is a specification.

This invention relates to an improved inner sole for shoes, which may be sewed into 10 the shoe as an integral part thereof when the shoe is made, or which may be slipped into the shoe as an accessory if desired.

An object of my invention is to produce 15 an inner sole in which greater flexibility and durability is attained lengthwise and side- wise at the ball of the foot than in other inner sole constructions known to me.

This and other objects are attained in the inner sole described in the following specification and illustrated in the accompanying drawing in which:—

Fig. 1 is a view of the underside of an inner sole embodying my invention.

Fig. 2 is a side elevation of the inner sole 25 shown in Fig. 1.

Fig. 3 is a view, similar to Fig. 1, but showing the upper side of my improved inner sole.

The inner sole embodying my invention 30 consists of a main portion 4 which is of leather, as is usual in inner soles, a top covering material of cloth 5, a bottom covering material of moisture proofed fabric 6 which extends only over the ball and toe 35 portion of the inner sole, a heel reinforcement of leather 7 and an arch supporting element of ribbed metal construction 8.

The main portion or body 4 is provided 40 with a series of perforations 9 which are spaced somewhat as shown in Figs. 1 and 3, but which are placed within the ball and

toe portion periphery sufficiently to leave a margin as shown, which will permit of the placing therein of stitches as in the Mackay and welt sole process.

An inner sole such as I have disclosed is particularly desirable in that it is extremely flexible and for this reason much more comfortable than inner soles of the usual type, especially for those having sensitive feet afflicted with calloused portions, and the like. An advantage I have attained over those inner sole constructions which are slotted, grooved, slit, etc., to produce flexibility, is that the material of the inner sole is not reduced in thickness and thereby weakened, because the original thickness of the leather is maintained throughout, besides allowing the finishing of outer edges of the shoe sole to be done smoothly and without the usual overhanging fibres of the slotted, grooved and slotted inner soles.

Having thus described my invention what I claim is:—

An integral inner sole for sewing onto the bottom soles and uppers of shoes in the course of construction, comprising a relatively flexible body portion having the ball and toe thereof for length-wise and side- wise flexibility perforated with cylindrical 70 apertures at substantially uniform distances from the edge to provide a rim for the reception of stitches for attachment to the bottom sole and upper of a shoe, a moisture proof layer of material to lie between the bottom sole and inner sole, an arch supporting element attached to the bottom, and a layer of material upon the upper portion of the inner sole used as a finisher thereof.

In witness whereof, I affix my signature.

THOMAS M. GYNAN.
